UNITED STATES PATENT OFFICE.

FRANK A. MCKINNEY, OF NEW BRUNSWICK, NEW JERSEY, ASSIGNOR TO WALKER-MCKINNEY CO., OF NEW BRUNSWICK, NEW JERSEY, A CORPORATION OF NEW JERSEY.

SOAP-HOLDER.

1,251,071.

Specification of Letters Patent. Patented Dec. 25, 1917.

Application filed May 12, 1917. Serial No. 168,065.

To all whom it may concern:

Be it known that I, FRANK A. MCKINNEY, a citizen of the United States, and a resident of New Brunswick, county of Middlesex, and State of New Jersey, have invented 5 certain new and useful Improvements in Soap-Holders, of which the following is a specification.

My invention relates to soap holders and 10 provides an attachment for a faucet whereby clean, clear water or water charged with soap in the form of suds can be obtained at will.

The object of the invention consists in 15 the improvement of articles of this character in a number of important respects whereby a simple, easily constructed and positively operating device may be obtained and one which is highly effective in operation, and with the foregoing and related 20 objects in view, my invention consists in the construction, parts, improvements and combinations herein set forth and claimed.

In the accompanying drawing I have 25 shown, for the purpose of affording a clear understanding of my invention, one form in which the invention may be embodied. In the said drawing, Figure 1 is a central, vertical cross-sectional view of a soap holder 30 embodying my invention. Fig. 2 is a fragmentary cross-sectional view showing a portion of Fig. 1 on an enlarged scale. Fig. 3 is a perspective view, with parts broken away, of a portion of the interior construction of a soap holder shown in Fig. 1. Fig. 4 is a front elevational view of a faucet with 35 the upper part of a soap holder embodying my invention in place thereon, and Fig. 5 is a perspective view of the detachable soap 40 containing receptacle.

In said drawing, reference numeral 10 designates the portion of the soap holder adapted to be secured directly to the faucet, and the same comprises a shell 11 and an 45 upwardly extending neck 12 provided with means for securing the device to a faucet, such means in the form shown comprising a rubber thimble 13 which is renewable, being held in place by a screw-threaded ring 14. 50 The shell 11 has a bottom 15 which is provided with a number of small jet holes 16, there being preferably about twenty-five to

thirty of such holes of a diameter preferably from fifteen-thousandths to twenty-thousandths of an inch, though the precise 55 number and dimension may be varied somewhat on either side of the particular figures given. The combined openings of these holes 16 are materially less than the opening of an ordinary faucet, so that the water, when 60 expelled through the openings 16, passes out as jets of great force. Centrally of the shell 11 and secured thereto and to the neck 12 is a tube 17 having lateral openings 18 65 therein. The tube 17 extends downwardly 70 beyond the bottom 15 and is provided below the openings 18 with a butterfly valve 19, the shaft 20 of which extends through the tube 17 and out through the flange 21 which skirts the lower margin of the shell 11. 75 The neck 12 and tube 17 may, of course, be integral if desired.

Means are provided for normally holding the valve 19 in a substantially vertical open position, and in the form shown a weight 75 22 is provided for that purpose, which also may serve conveniently as a crank or thumb piece for conveniently turning the valve 19 to closed position at right angles to that shown. It should be noted that the valve 80 19 is preferably held closed by pushing upward on the crank, whereby the device is more firmly held in place on a faucet.

The parts so far described comprise all those which are attached directly to the 85 faucet, and it will be observed that with the valve 19 in the position shown, the water will pass clear through the valve 19, whereas with the valve 19 closed, the water passes through the lateral openings 18 in the tube 90 17 and into the chamber in the shell 11 and is discharged with considerable violence through the spray openings 16, and at the same time, the passage of the water being retarded, a hydraulic pressure of the water 95 against the exterior of the thimble 13 is obtained, and by this hydraulic back pressure the device is very firmly held on the faucet in a manner which will be readily understood. Should the thimble 13 become 100 worn and leaky, as may happen after a period of use, so that water gets between it and the faucet spout, thereby preventing the effective holding by the back pressure

means described, the thimble 13 may be readily replaced by unscrewing the ring 14 and a fresh rubber thimble substituted.

23 designates the soap containing shell, 5 preferably of glass, though other materials may be used, and means are provided for detachably securing it to the shell 11 and for affording a tight joint therebetween when in place therein. In the form shown 10 the member 23 is provided with three slots 24, and the flange 21 of the shell 11 is provided with three cooperating inwardly projecting portions 25 formed, in the construction shown, by indenting the material of the 15 flange inwardly at separated points. A packing ring, as the rubber ring 26, is seated within the flange 21 and against the bottom plate 15 of the shell 11 and serves in an obvious way to make the joint between the 20 member 23 and the flange 21 tight. The rubber ring 26 is preferably cut apart at one side and the cut ends 27 so placed that the valve shaft 20 is received therebetween, the compression of the rubber ring by the 25 member 23 being screwed in place, and also the tendency of the ring to expand and thereby bring the ends together tightly, serving to prevent leakage about the shaft 20. The member 23 has a spout 28 in which 30 is received a tube 29 which telescopes with and surrounds the lower end of the tube 17, whereby water discharged from the tube 17 may pass readily through the tube 29, and said tube 29 near its lower end has lateral 35 openings 30 to permit water and soap suds to pass into the interior of the tube 29 therethrough, and means are provided in the member 23 for sustaining a cake or pieces of soap in place therein. Such sustaining means 40 may be of any preferred form, but in the construction shown a metallic plate 31 having apertures 32 is secured to the tube 29. Various other supporting means may be utilized, and, if preferred, the same need not be 45 secured to the tube 29.

The operation of the device will be readily understood from the foregoing. With the construction shown, the tube 29 and the soap supporting member 31, attached together as 50 shown in Fig. 3, are set in place in the member 23 in the relation shown in Fig. 1, and pieces of soap or a properly shaped cake of soap is put in the holder 23 upon the holding means 31 and surrounding the tube 29, 55 and the member 23 is then attached to the member 10, the projections 25 being received in the slots 24 and the tube 17 within the tube 29 and the member 23 rotated a short distance, whereupon the parts are firmly 60 held together, and the ring 26 is compressed, making a tight joint. When the soap is exhausted the shell 23 is rotated slightly in reverse direction and is readily taken off and replaced with new soap in place therein.

The device does not interfere with the ordinary use of the faucet as the valve 19 is normally held in vertical or open position by the weight 22 or other means provided for that purpose, and the stream of water issuing from the faucet passes clearly 7 through the tubes 17 and 29, which afford a free passage considerably in excess of the faucet opening, and is discharged without making any contact with the soap, and fresh, clear water is obtained. To obtain soapy 75 water or soap suds, the valve 19 is turned to closed position, whereupon the water, being discharged forcibly through the holes 16, strikes upon the soap within the holder 23 and dissolves the same, forming it into 80 soap suds which pass through the openings 30 and is discharged through the tube 29. This action of forming suds is, of course, more efficient with heated water than with cold. If moderately soapy water is desired 85 to be obtained, the valve 19 may be permitted to remain slightly open. It will be noted that the soap lies under the jets and that all the jets play on the soap until it is used up, a result not possible to be secured 90 with laterally directed jets, for example.

I found that with a device constructed as shown, there is substantially no contamination by the soap of the clear water running directly through the tubes. For example, I 95 have found that, after using the device for a considerable period, say a minute or more, for the production of soap suds, with the valve 19 closed and then opening the valve and allowing the water to run freely through 100 the tubes 17 and 29 for a few seconds, say four or five seconds, the water discharged thereafter is entirely free from soap, and I have frequently tested the water obtained under such conditions with a delicate chemical test for soap and have found that no trace of soap was present even after boiling the water down to one-twentieth or thereabout of its original volume and then subjecting the water remaining, with all impurities therein concentrated to substantially the extent illustrated, to delicate chemical 105 tests for the presence of soap, and in such instances have found soap to be entirely absent from the water.

It will be understood that the embodiment illustrated is intended only for the purpose of affording a clear understanding of my invention, and that I am not to be limited thereto except as required by my claims, by 110 which my invention is defined, and that modifications and changes therein may be resorted to without departing from my invention or sacrificing any of its advantages.

Having thus described my invention, I 115 claim:

1. In a soap holder, a shell, means for attaching same to a faucet, a central pipe in

- said shell and having lateral openings communicating with the hollow interior of the shell near the top thereof, a butterfly valve in said pipe beneath said lateral openings, 5 detachable means for holding soap beneath said shell and under the spray openings, a discharge tube, and means below said valve for providing communication between said soap containing chamber and said discharge 10 tube.
2. In a soap holder, means adapted to be removably attached to a faucet for permitting the discharge of clear water or for charging the water with soap in solution, 15 and manually operated control means therefor, said control means being adapted to be operated by upward pressure, whereby the holding of the device on the faucet is assisted.
- 20 3. In a soap holder, a shell provided with downwardly projecting jet holes, a tube in said shell having holes leading into the shell and having a valve beneath said holes, means for supporting soap in line with the jet openings and permitting its discharge 25 when charged with soap, and means for holding said valve closed by upward manual pressure, such pressure operating to assist in holding the tube in place on the 30 faucet.
4. In a soap holder, means comprising a central tube and a surrounding annular soap holding chamber, passages being provided between the tube and the soap chamber, and 35 a valve in said tube beneath said passages, said valve being adapted to be held closed by manually exerted upward pressure, whereby the holding of the device upon the faucet is assisted.
- 40 5. In a soap holder, a shell adapted to be secured to a faucet and provided with a central passage and with spray holes in its bottom, means for opening and closing said passage whereby the water from the faucet 45 may be discharged through said passage or through the spray holes at will, a soap holding cup having a central passage and a surrounding receptacle for soap and adapted to be detachably secured to said shell with said 50 passages in alinement and the soap supported beneath said spray openings, whereby clear water may be passed through the central passage or the water discharged through the spray openings to charge the water with 55 soap suds at will.
6. In a soap holder, a shell, means for attaching the same to a faucet so that the shell is supported substantially vertically, downwardly directed spray openings in the bottom of the shell, a central tube in said shell, means for permitting water to pass 60 through said central tube or for diverting it into said shell and causing it to pass downwardly through said spray openings, a soap holding cup having a central tube 65 alinement with the first named tube and having a surrounding annular chamber for supporting soap beneath and in line with the discharge from said spray openings, openings being provided from the soap chamber into 70 the tube in the cup, and means for detachably connecting said cup to said shell.
7. In a soap holder, a hollow shell having a central tube provided with lateral openings extending into the shell, means for attaching said shell to a faucet so that the spray openings are directed downwardly, a valve in said tube below the lateral openings therein and provided with means for normally maintaining it in open position but adapted to be held manually in closed position, a detachable cup having a bayonet joint connection to said shell, a gasket in said shell for making a tight joint between it and the cup, said cup having a central tube 75 in alinement with the tube in the shell, and having means surrounding said tube for supporting soap beneath the spray openings, there being lateral openings in the tube beneath the soap supporting means for permitting water passing through said soap chamber to reenter the tube below the shell.
8. In a soap holder, a hollow shell provided with downwardly directed spray openings, a central tube in said shell, means for 80 attaching said tube to a faucet, said tube being provided with openings communicating with the interior of the shell, a butterfly valve in said tube beneath said openings, a shaft for said valve extending 85 through the tube and through a flange projecting downwardly on the shell beneath the bottom thereof and provided with a cranked arm and a weight thereon adapted to maintain the valve in open position, but whereby 90 the valve may be manually closed, and means adapted to be detachably connected with the flange on said shell for supporting soap in line with the spray apertures, whereby 95 water passing through the said soap chamber may be charged with soap, and also provided with a central tube adapted to register with the tube in said shell.
9. In a soap holder, a shell having downwardly directed jet apertures and a central tube, a rubber thimble in said tube whereby the same may be secured upon a faucet with the thimble hugging the end of the faucet close and subjected to water pressure on its exterior, the jet apertures in the shell being minute and adapted to retard the 115 flow of water and cause the forcible discharge of water in jets therethrough, a valve in said tube adapted to prevent the passage of water therethrough and divert it through 120 the jets, a handle for operating said valve, said handle extending to the exterior of the device and being adapted to close the valve.

4
by upward pressure thereon, whereby the hold of the apparatus on the device is assisted, soap containing means adapted to be detachably supported by said shell and comprising a central tube in line with the tube in the shell, and a surrounding annular soap chamber provided with apertures communi-

cating with said tube near the lower end thereof.

In testimony that I claim the foregoing, 10 I have hereto set my hand, this 5th day of May, 1917.

FRANK A. McKINNEY.
